UNITED STATES PATENT OFFICE.

WALTER H. COTTON, OF CHICAGO, ILLINOIS, ASSIGNOR TO UNION DRAFT GEAR CO.,
A CORPORATION OF ILLINOIS.

DRAFT GEAR.

Application filed September 1, 1923. Serial No. 660,501.

To all whom it may concern:

Be it known that I, WALTER H. COTTON, a citizen of the United States, and resident of Chicago, county of Cook, and State of Illinois, have invented certain new and useful Improvements in Draft Gears, of which the following is a specification, and which are illustrated in the accompanying drawings, forming a part thereof.

10 The invention relates to draft gears for railway cars of the friction type.

Its objects are to secure simplicity of construction coupled with high efficiency, and it consists of a structure such as is 15 hereinafter described, and is illustrated in the accompanying drawings, in which—

Fig. 1 is a central plan section of the gear, certain parts of the car frame being shown in detail;

20 Fig. 2 is a plan view of the gear as applied to a car, showing the gear compressed; the gear is shown partly in plan and partly in central section;

Fig. 3 is a detail side elevation of the 25 gear and coupling, a part of the gear being shown in central vertical section; and

Fig. 4 is a sectional detail on the line 4—4 of Fig. 1.

There is represented at 10—10 a pair of 30 center or draft sills of a railway car, each being provided with the usual draft lugs 11—11 and buffering lugs 12—12.

The butt end of a coupler bar is shown 35 at 13, and its extension, tail-strap or yoke at 14.

The parts thus far mentioned are of any desired or ordinary construction and form no part of the invention.

The improved draft gear comprises a follower 15, of the chambered type, having side walls 16, 17 and top and bottom walls 18, 19. Opposed to the follower 15 is a plate follower 20. As the gear is shown the follower 15 cooperates with the draft lugs 40 11, 11 and the follower 20 with the buffering lugs 12, 12. The relative positions of the two followers may however be reversed without affecting the operation of the gear.

45 The inner face of the follower 20 is flat and against it are seated two substantially triangular wedge blocks 21, 22, the adjacent angles of the two blocks however being cut away to provide flat meeting faces for the

blocks when the gear is in normal or released position as shown in Fig. 1. 55

A wedge block 23 shown as having the form of a truncated cone has its apex entered between adjacent inclined faces of the blocks 21, 22, the base of the block 23 being seated, in the released position of the gear, against a plate 24 which constitutes a spring seat. Friction blocks 25, 26 are seated against the side walls 16, 17, of the follower 15 and have inclined faces complementary to and bearing against the outer 65 faces of the wedge blocks 21, 22. In the released position of the gear the outer ends of the blocks 25, 26 project into and to the bottom of recesses 28, 29 formed in the inner face of the follower 20. 70

The outer faces of the blocks 25, 26, bear against the side walls 16, 17, of the follower 15, and their inner ends bear upon the plate 24. Springs, shown as two sets of nested helicals, 30, 31, are interposed and react 75 between the end wall of the follower 15 and the plate 24. Stop shoulders 32, 33, are formed on the top and bottom walls 18, 19, of the follower 15, for limiting the inward movement of the wedge block 23 as the 80 gears compress. Preferably, as shown in Fig. 3, these shoulders are spaced a short distance from the block 23 in the normal position of the gear, though if desired the block may be seated normally against them. 85 The shoulders 32, 33, may, as shown, constitute the ends of depressed portions of the walls 18, 19, which extend to the end wall of the follower 15. By this configuration of the walls the shoulders are greatly 90 strengthened and any tendency to break off that might exist if stop lugs were used is obviated.

When the wedge-block 23 and the shoulders 32, 33, are normally out of engagement, 95 all of the wedging and friction elements move together until the parts named make contact, the resistance of the initial compression of the gear being only that afforded by the springs.

When the block 23 is in or comes into engagement with the shoulders 32, 33, its apex is forced inwardly between the blocks 21, 22, as the two followers move toward each other, spreading these blocks which in 105 turn force the blocks 25, 26, inwardly with

reference to the followers 15, compressing the springs. Over compression is prevented when the follower 20 comes into contact with the wedge-block 23, or with the side, top 5 and bottom walls of the follower 15.

As the gear is compressed friction is developed not only between the several wedges, but also between the bases of the blocks 21, 22, and the follower 20, and between the 10 outer faces of the shoes 25, 26, and the side walls of the follower 15.

When the compressive stresses are relieved the parts return to normal position, as shown in Fig. 1, by reason of the expansion of the springs. The action is the same 15 in both draft and buffing.

The gear is easily assembled, is simple and comparatively cheap of construction, no machining of the parts being required.

20 While a preferred embodiment of the invention is disclosed, changes of detail may be made without departing from its scope.

I claim as my invention:

1. A draft gear comprising, in combination, a chambered follower, a plate follower, a pair of triangular wedge blocks seated against the plate follower, a pair of friction blocks engageable with the side walls of the chambered follower and having inclined faces engaging the wedge blocks, a wedge block interposed between the triangular blocks, spring means resisting longitudinal movement of the friction blocks, and stops limiting relative movement 30 of the interposed wedge block and the chambered follower during the compressive movement of the gear.

2. A draft gear comprising in combination a chambered follower, a spring housed 40 within the chamber and reacting against its end wall, a plate forming a seat for the opposite end of the spring, an opposed follower, a pair of triangular wedge blocks slidably engaging the inner face of the opposed follower, a pair of friction blocks seated against the plate and side walls of the chambered follower and having inclined faces engaging the outer faces of the triangular blocks, a wedge block interposed between the triangular blocks, and stops for limiting relative movement of the chambered follower and the last-named wedge block during the compressive movement of the gear.

55 3. A draft gear comprising in combination a chambered follower, a spring housed

within the chamber and reacting against its end wall, a plate forming a seat for the opposite end of the spring, an opposed follower, a pair of triangular wedge blocks 60 slidably engaging the inner face of the opposed follower, a pair of friction blocks seated against the plate and side walls of the chambered follower and having inclined faces engaging the outer faces of the triangular blocks, a wedge block interposed between the triangular blocks, and stops for limiting relative movement of the chambered follower and the last-named wedge block, such stops being normally spaced 65 from the blocks.

4. In a draft gear, in combination, a chambered follower having forwardly facing shoulders on two of its longitudinal walls, an opposed follower, wedging friction shoes engaging longitudinal walls of the chambered follower, springs reacting between the shoes and the end wall of the chambered follower, a pair of triangular wedge blocks 75 slidably engaging the opposed follower and inclined faces of the shoes, and a wedge block loosely interposed between the triangular blocks and engageable with the forwardly directed shoulders.

5. A draft gear comprising, in combination, a chambered follower, a plate follower, a pair of triangular wedge blocks seated against the plate follower, a pair of friction blocks engageable with the side walls of the chambered follower and having inclined faces engaging the wedge blocks, a wedge block interposed between the triangular blocks, spring means resisting longitudinal movement of the friction blocks, and a positive seat carried by and extending 90 across the chambered follower for the interposed wedge block.

6. The combination in a draft gear of a chambered follower having forwardly facing shoulders near its inner end, an opposed plate follower, a pair of triangular wedge-blocks seated against the plate follower, a pair of friction blocks seated against side walls of the chambered follower and having inclined faces engaging the triangular blocks, a wedge-block interposed between the triangular blocks and engageable by the shoulders on the compressive movement of the gear, and a spring 100 resisting longitudinal movement of the shoes 105 into the chambered follower.

WALTER H. COTTON.
